GAS GRILL

Lewis H. Herr, Lansdale, Pa., assignor to
Caloric Corporation, Topton, Pa.

Filed Dec. 19, 1969, Ser. No. 20,568

Term of patent 14 years

Int. Cl. D7—04

U.S. Cl. D81—10

FIG. 1

FIG. 2

FIG. 3

FIG. 4

FIG. 5

FIG. 1 is an isometric view showing the front, top and one side of a gas grill embodying the invention; and

FIGS. 2-5 are front, rear, side and opposite end elevational views of the gas grill shown in FIG. 1.

I claim:

The ornamental design for a gas grill, as shown.
